UNITED STATES PATENT OFFICE

2,490,016

WINDOW SHADE FIXTURE

Frederick A. Cooper, Bluefield, W. Va.

Application December 14, 1945, Serial No. 634,951

2 Claims. (Cl. 248—271)

1

This invention relates to novel functional improvements and structural refinements in new type fixtures such as are used for hanging window shades, roller-equipped charts, maps and the like, and the principal object of the invention is to generally, specifically and otherwise improve upon similarly constructed fixtures and brackets.

An equally important, if not a more important, object of the invention is to provide a two-part fixture, one part constituting a base applicable and attachable to the stationary window frame, and the other part being in the form of a bracket, shiftably and adjustably mounted on said base, said bracket being of general L-shaped form and expressly constructed to lend itself to ready hand adjustments, whereby, upon employing a pair of correspondingly constructed fixtures, each with shiftable brackets, said brackets may be individually and collectively adjusted and arranged to better accommodate the shade roller pintles.

A further object of the invention has to do with the provision of twin or adjustable fixtures which are such in construction as to promote manufacturing advantages such as economy, simplicity, expedient assembly of parts, and to thus produce fixtures which are easy to handle and install.

Although the invention is illustrated in the drawings, and herein described for use, primarily, in accommodating conventional or standard types of window blinds and shades, it is obvious that, as before indicated, said fixtures lend themselves admirably well for use in hanging and properly supporting a spring wound roller equipped with such articles as maps, pictures, charts and items utilized in educational establishments, schools, lecture halls and the like.

Other objects, features and advantages of the invention will become more readily apparent from the following description and the accompanying illustrative drawings.

In the drawings, wherein like numerals are employed to designate like parts throughout the views:

Figure 1 is a top plan view (or alternatively a face elevation) of a fixture constructed in accordance with the principles of the instant invention, this being the so-called left-hand fixture.

Figure 2 is an end view of the same, that is a view observing the construction of Figure 1 in a direction from left to right.

Figure 3 is a central longitudinal sectional view on the plane of the line 3—3 of Figure 1.

2

Figure 4 is a view like Figure 1, that is a face elevation or top plan, whichever way viewed, the same representing a duplicate but right-hand fixture.

5 Figure 5 is an end view observing Figure 4 in a direction from left to right.

Figure 6 is a central longitudinal sectional view on the plane of the line 6—6 of Figure 4.

10 Figure 7 is a plan view of the sheet metal blank or pattern from which the attachable base unit is fashioned.

15 Although, except for a slight detail, both fixtures are the same in construction, I have chosen to illustrate both left and right-hand fixtures in order to provide a clearer and more comprehensive understanding of the invention. Since it would perhaps be repetitious to describe each detail of each fixture separately, it is believed that it is best to combine the description but to provide a preliminary foundation. For example, as already indicated, the left-hand fixture is denoted by the reference character A while the entire right-hand fixture is differentiated by the reference character B. The base unit in each fixture is the same and for that reason a description of one will suffice for both. Generally construed said base fixture is denoted by the numeral 10. It is fashioned from the winged blank illustrated in Figure 7. Thus, and as here

20 seen, it comprises a rectangular body or attachment plate 11 having holes 12 at opposite ends to facilitate fastening said plate to the window frame or other support (not shown). Along intermediate portions of its opposite longitudinal edges said plate is provided with outstanding flanges 13. Each flange has its free end 14 bent into a lip which is parallel to the flange 13 and the flange 13 is bent at right angles to the plate. This leaves the intervening bend 15 in a horizontal position spaced from the plate. The lip 14

25 is also spaced from the plate and by thus bending the parts 13, 14 and 15, I provide spaced parallel guide channels along opposite median portions of said plate. As stated, the attachment unit just described is the same in both fixtures

A and B.

30 Cooperable with each base unit is an L-shaped bracket and this is also fashioned from a single sheet of material such as metal of appropriate gauge and said bracket is denoted, as a unit, by the numeral 16. The lateral shoe or foot portion 17 is provided along longitudinal edges with guide flanges 18 which fit in said guide channels. One end of the foot 17 is slotted to provide an

35 intervening tongue 19 and said tongue is pro-

vided with a return bend which fits between the lips 14 of the respective guide channels and said return bend forms a finger grip as well as a stabilizing element. At the outer end each bracket is provided with an outstanding so-called head portion 20 having a bearing means therein to accommodate the pintle or journal pin (not shown) on the shade or other part which is to be suspended. At this point the only difference between the respective heads 20 of the two brackets is that the one at the left is provided with a slot 21 opening into a kerf 22, while the one at the right is provided with an indentation 23 having a circular bearing hole to accommodate the usual cylindrical pintle on the coacting end of the shade (not shown).

Novelty is predicated upon the simple double winged rectangular blank in Figure 7 with the wing extensions bendable to form a series of flanges which in turn define longitudinal guide channels, said channels having their opposite ends terminating inwardly of the opposite outer ends of the plate 11 in order to expose the holes 12 for anchoring the base in position on the window frame and also to provide an effective shiftable surface for the relatively slidable part or foot 17 of the bracket 16. Novelty is also predicated upon the particular L-shaped bracket 16 with one end forming the apertured bearing head and the opposite end forming a shoe which is slidable against the base, said shoe having flanges which slide back and forth in the guide channels and also terminating in a return bend 19 which forms a finger grip. This makes it possible to utilize a finger grip 19 for exerting endwise stress against the bracket to push it back and forth. Or, the thrust action can be utilized against the head 20. In other words, it is possible for the user to catch hold of either end of the bracket to shift it back and forth with relation to the base unit.

Whereas the previous description sets out the fact that the foot or shoe 17 has one end formed with parallel slits to define the stated tongue 19, I desire to be understood that the "slitting" step is not essential since one end of the shoe may be provided with a relatively narrow extension and the extension may be rolled or bent upon itself to define the return bend or finger-grip as it has been described. In connection with this phase of the invention I desire to call attention to the fact that the two brackets will be produced by a metal stamping procedure and when they are brought together in the relatively slidable or assembled relationship shown in the drawings, the flanges 18 will fit rather snugly and will be held substantially by friction in the coacting guide channels. In most instances the interrelationship of flanges 18 and guide channels will be such that it may not be possible to slide the bracket 16 with a slight press of one's finger. In this case the so-called finger-piece 19 would function as an abutment and a screwdriver or other tool could be used to "tap" the bracket 16 for adjustment in relation to the base bracket 10.

I call attention also to the fact that the shoe portion 17 of bracket 16 is shown to be approximately of the same area as the body of the base bracket. In practice, the shoe will actually be of the same area. That is to say, the shoe will match the body of the base in area proportions at the time of actual manufacture and sale.

I would also call attention to the fact that all of the base brackets will be of identical construction and may be interchangeably used.

Thus, there is no "left" or "right" requirements in respect to the base brackets 10. Either end may be nailed in place and, therefore, this part of the assembly is substantially fool-proof, as is obvious. Then, too, when the respective base plates of a pair of fixtures are nailed in place, the outer ends will be substantially flush with the edge portions of the rollable shade. Consequently, when the complete brackets are assembled, that is, when the brackets 16 are attached to the then nailed base brackets, the major portions of the fixtures will be hidden from view since the shade will overlie the fixtures. In most devices which have come to my attention, either one or the other part of the fixture projects from beneath the shade and constitute an "eye sore."

Briefly reviewed, novelty is thought to reside in a relatively stationary base unit or bracket 20 embodying flat rectangular plate having longitudinally extending open-ended guide channels and serving as a support for a relatively adjustable L-shaped bracket or unit. When the two brackets are assembled, as shown in the drawings, the longer limb of the L-shaped bracket functions as a shoe and is superimposed upon and in slidable contact with the body of the base bracket and has its longitudinal reinforcing flanges interlocked and slidable in the relatively fixed guide channels of the base bracket. What with the other limb of the L-shaped bracket constituting a proper adapter and support for a shade roller, and the opposite end of the shoe formed with a return bend providing a finger-grip, a novel association and arrangement of elements is had.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A window shade fixture of the class shown and described, a relatively stationary bracket embodying a base plate of general rectangular form provided at opposite ends with nail holes and provided on intermediate longitudinally edge portions with right angularly bent flanges, the free edges of said flanges being bent inwardly toward each other and then downwardly toward the body portion of the plate and serving to provide open-ended guide channels, a complementary L-shaped bracket, the latter being separable from the base bracket, and being movable in relation to the base plate, one limb of said L-shaped bracket constituting a flat assembling shoe of an area nearly equal to the area of said base plate and superimposed upon said base plate and being provided with lateral assembling flanges, said flanges fitting slidably into said guide channels, the other limb of said L-shaped bracket constituting a shade roller accommodating head, said head being at what is normally the outer end of said shoe, the opposite end of said shoe being provided with a tongue, said tongue being bent upon itself and overlying the body portion of the shoe and providing a return bend, said return bend being of width less than the space between said guide channels and constituting a finger-grip.

2. An adjustable window shade fixture comprising two companion brackets, a relatively stationary base bracket and a relatively movable L-shaped adjusting bracket, said base bracket embodying a base plate of general rectangular form provided at opposite end portions with in-corner positioned nail holes and provided on intermediate longitudinal edge portions with right angularly bent flanges, the free edges of said flanges being bent inwardly toward each and then bent downwardly toward the body portion of the plate and serving to provide a pair of spaced parallel open-ended guide channels, said guide channels having their respective open ends terminating inwardly of the opposite ends of the base plate, said L-shaped bracket being readily attachable to and detachable from said base bracket, one limb of said L-shaped bracket constituting a flat assembling shoe, said shoe being superimposed upon said base plate, being of an area substantially equal to the area of the base plate and being provided along longitudinal edges with lateral keying and assembling flanges, the flanges being of lengths commensurate with the length of the shoe, said flanges fitting slidably in 25 said guide channels, the other limb of said L-shaped bracket constituting a shade roller ac-

commodating head and being apertured, said head being at one end of the shoe, the opposite end of said shoe being provided with a return bend overlying the body portion of the shoe and constituting a reinforcing member and also functioning as a finger-piece, said finger-piece being free of sliding contact with the adjacent inner walls of said guide channels.
